UNITED STATES PATENT OFFICE.

FRANK S. REINHARDT, OF MEMPHIS, TENNESSEE.

BALE-TIE.

1,177,355.

Specification of Letters Patent. Patented Mar. 28, 1916.

Application filed May 4, 1915. Serial No. 25,703.

To all whom it may concern:

Be it known that I, FRANK S. REINHARDT, a citizen of the United States of America, and a resident of Memphis, county of Shelby, 5 State of Tennessee, have invented certain new and useful Improvements in Bale-Ties, of which the following is a full and clear specification, reference being had to the accompanying drawings, in which—

10 Figure 1 is a sectional view of my improved buckle as it appears in use; Fig. 2 a front elevation of the same, the bale being omitted in both views; and Fig. 3 is a transverse section on the line 3—3 of Fig. 2.

15 The object of my invention is to provide a buckle which shall be simple and inexpensive to manufacture and to apply, and which at the same time shall be so constructed that slipping of the bale-band through the buckle 20 will be rendered practically impossible, irrespective of the bale pressure on the band, as more fully hereinafter set forth.

25 My buckle consists of a metal plate *a* provided at its upper edge with a transverse slot *b* through which, in the usual manner, the depending end of the bale-band is passed to connect the buckle thereto. Across the lower end of the plate *a* is formed another slot *c* somewhat longer than the width of the band, 30 but having its lower edge *d* shorter than the width of the band, the end walls *e* of this slot being inclined from where they join the lower edge *d* upwardly. Formed integrally with the plate, along the upper edge of the 35 slot *c* is a pair of inwardly extending teeth *f*, each of which is tapered to substantially a V form. These teeth *f* are transversely in alinement and are separated a sufficient distance to cause their pointed ends to lie in the 40 path of the band at the respective side edges thereof.

45 In applying my device, the depending end of the band is looped through the upper slot *b* in the usual manner, its free extremity 50 lying against the inner face of the band at a point above the buckle. The other end of the band is passed through the slot *c* and drawn upwardly past the teeth *f* and arranged so that its upper extremity will lie 55 against the inner face of the band at a point above the buckle. With the band arranged in this manner, it will be seen that when the bale is released from the press and allowed to expand, the pressure will draw the band 60 taut and thus cause the edges of the band to be crimped at *g* by the inclined cam edges *e*

and be indented at *h*, at opposite edges of the band, by means of the prongs or teeth *f*. Thus crimping or bending the edges of the band where it engages the buckle provides 60 an effective and simple means for preventing slippage of the band, and this means for preventing slippage will be just as effective with a lightly pressed bale as with a heavily 65 pressed one.

A feature of importance lies in utilizing the expansive tendency of the bale to bring about the interlocking of the buckle and the band, and it will be seen also that the interlocking is made especially effectual by reason of the fact that the crimps or indentations *h* are made in a direction opposite to the crimps or bends *g*.

It will be observed that with my construction, the interlocking of the band with the 75 buckle at the points *g* may be obtained without notching the edges of the band, the edges of the band being smooth and straight as with the common form of bale band. As is 80 obvious, notches not only weaken the band but also add materially to its cost of manufacture and it is, therefore, greatly advantageous to avoid their use. It will be seen also that in order to do away with the notches in the edges of the band and cause 85 the interlocking crimps at *g* to be automatically formed when the band is drawn taut, it is essential that means be provided at the upper edge of the slot *c* which shall extend inwardly and cause an abrupt inward bend in 90 the band and thus insure the crimping at *g* when the band is drawn taut. It will be observed further that my buckle is self-fastening; that it can be tied or fastened without 95 the necessity of first bending the free end of the band; that it eliminates the possibility of initial slack in the band or in the buckle; that the initial tightness does not depend upon the accuracy of the laborer who applies the buckle; that it is impossible to apply the buckle incorrectly, since if applied at all the band will be held firmly and permanently in its initial position; and that the greater the strain on the band the tighter it will be held by the buckle.

Having thus described my invention, what I claim is:

1. A bale banding device consisting of a straight-edged band, a tie-buckle consisting of a plate having means at one end for attachment to one end of the band and also provided with a transverse slot near its other

- end, this slot being longer than the width of the band and having one of its edges shorter than the width of the band, the end walls of the slot being inclined from their juncture 5 with said shorter edge toward the longer edge of the slot, laterally-extending means being provided at the longer edge of the slot for causing an abrupt bend in the band, for the purposes herein set forth.
- 10 2. A bale banding device consisting of a straight-edged band, a tie-buckle consisting of a plate having means at one end for attachment to one end of the band and also provided with a transverse slot near its other 15 end, this slot being longer than the width of the band and having one of its edges shorter than the width of the band, the end walls of the slot being inclined from their juncture

with said shorter edge toward the longer edge of the slot, laterally-extending means 20 being provided at the longer edge of the slot for causing an abrupt bend in the band, said laterally-extending means consisting of a pair of separated teeth located in the path of the opposite edges of the band, whereby 25 when the free end of the band is threaded through the slot and passed behind said teeth the expansive tendency of the bale will cause said teeth to crimp the two edges of the band and the said inclined end walls will 30 crimp the two edges of the band in the opposite direction.

In testimony whereof I hereunto affix my signature.

FRANK S. REINHARDT.
